UNITED STATES PATENT OFFICE.

ELIE W. LABOMBARDE, OF NASHUA, NEW HAMPSHIRE.

DOUBLE-WALL BOX AND METHOD OF MAKING THE SAME.

Application filed April 10, 1922. Serial No. 551,031.

To all whom it may concern:

Be it known that I, ELIE W. LABOMBARDE, a citizen of the United States, and resident of Nashua, in the county of Hillsboro and State of New Hampshire, have invented certain new and useful Improvements in Double-Wall Boxes and Methods of Making the Same, of which the following is a specification.

This invention relates to boxes made of paper stock of the kind usually referred to as box board, and has particular reference to boxes made of blanks marginal portions of which are adapted to form double-thick side and end walls.

One of the objects of my present invention is to provide boxes of this type which can be stored or shipped in flat condition and can then be quickly set up or converted to well-secured receptacle form by the users, when wanted, without requiring any adhesive to hold them in set up condition.

Another object is to provide an economical method of manufacturing the blanks with portions which will interlock, when set up, and will reliably remain interlocked.

With these and other objects in view, the invention consists in the method and in the blank and box substantially as hereinafter described and claimed.

Of the accompanying drawings:—

Figure 1 is a plan view of one end portion of a blank formed according to my invention, it being understood that the other end (omitted to reduce space) will be a duplicate of the end illustrated.

Figures 2, 3, 4 and 5, are sectional perspective views illustrating successive steps in the formation of a box member.

Figure 6 represents a section on line 6—6 of Figure 5 on a larger scale.

Similar reference characters designate similar parts in all of the views.

Referring first to Figure 1, the box board is cut and creased to form a blank comprising a central portion 12, side wall sections 13, 14, and end wall sections 15, 16, the latter having an edge flap 17. The ends of section 13 have foldable tongue flaps 18, and the ends of sections 14 have foldable tongue flaps 19. While the sections 13, 14, are of substantially equal width, the flaps 19 of the outer wall sections 14 are of considerably less width than the flaps 18 of the inner wall sections 13 for a reason explained hereinafter.

The dotted lines designated by reference letters *a* to *h* inclusive represent the lines along which the blank is creased when made.

The outer wall sections 14 have edge notches or recesses 20, and end notches or recesses 21, the latter being cut away to a point slightly past the line of crease *d*. These recesses are to aid in the interlocking of the wall sections as will be explained in connection with Figures 5 and 6.

When the blank is cut each end flap or section 17 has one or more extensions or tabs 22 transversely creased as at *h*. Preferably there are three of such tabs as illustrated in Figure 1, but obviously there may be but one in which case that one would be nearly if not quite as long as the flap 17.

I will now describe the method of treating the blank to prepare it for conversion to locked set up condition, said treatment including the transfer of the end tabs 22 onto the central portion 12 and securing them there in accurate positions to present locking members.

The side wall sections 14 are folded onto the sections 13 and adhesively secured thereto (Fig. 2) the tongues 18, 19, being left loose, as flaps. At or about the same time the end sections 16 are folded over onto sections 15, the flaps 17 and their tabs reaching onto the portions 12. Before this, by machinery or otherwise, glue is applied to those areas of the tabs 22 between their tip edges and the crease lines *h*. Said tabs are pressed down until the glue sets.

Next, a cutting operation severs the tabs 22 along a line parallel with but a short distance from the crease lines *h*. The cutter may be a rotary one such as a disk knife indicated at *X* in Figure 3. This leaves the sections 15, 16, 17 free to be returned to outward position as in Figure 4, after which a second cutting operation, as by a disk knife *Y*, trims away the remaining portions of the tabs so as to leave the section 17 with a straight edge.

The reason for cutting on two lines is to remove enough of the tabs between the glued areas and the edge of the section 17 to avoid crowding when the sections 17, 16 and 15 are bent on the lines *g*, *f*, *e*, to the angular form shown in Figure 5.

I do not limit myself to performing the cutting operations successively, in order to remove portions of the tabs, as the entire width of the portions to be cut away may

be removed by cutting operations simultaneously performed, or by a single cutter of requisite width.

Owing to the fact that only those areas of 5 the tabs between their tip edges and the crease lines h are glued to the portions 12, the unglued areas or lips 22^a on the other sides of the lines h (Figs. 4, 5 and 6) are free to permit the edge of the section 17 10 to extend thereunder when the blank is set up as presently described.

When the blanks are finished for storage or shipment, they are in the condition shown by Figure 4 but with the edge of section 17 trimmed straight. Then, when a blank 15 is to be set up for use, the sections 14, 13, already glued together, are turned up perpendicular to the central portion 12, the tongue flaps 18, 19, are turned in as indicated 20 by dotted lines in Figure 5, and the end sections 15, 16 are folded up and over the flaps 18, 19, and the edge of section 17 is snapped under the free lips 22^a of the members 22 which now form stops or catches for 25 said edge of section 17. At the same time, the ends of section 17 extend into the recesses 20 of sections 14.

The reason for making the flaps 19 narrower than the flaps 18 is best illustrated by 30 Figure 6. By comparing Figures 5 and 6 it will be understood that each end portion of section 16 extends down inside of so as to overlap two thicknesses of material, viz: two flaps 18, 19. The lower edge of flap 19, 35 being now higher than the lower edge of flap 18, the section 16 is necessarily somewhat curved or bent back (see Fig. 6) when section 17 is engaged by the stop or lock lips 22^a. As the material of which the blank is 40 made has a normal tendency to spring back to flat or straight condition, unless scored or creased, the flexing of section 16 in order to snap the edge of section 17 into locking engagement with the lips 22^a, causes said 45 edge of section 17 to always possess a tendency to retain said locking engagement. Unlocking can only be effected by a determined effort to push or spring back the section 17 throughout its length and then, 50 while so pushing it back, lift its edge clear of the lips 22^a and its ends clear from the recesses 20, 21. As the section 17, when bent as shown by Figures 5 and 6, has a constant 55 tendency to bear down on the section 12, it adds to the difficulty of unlocking the parts. With care and patience the folded parts can be unlocked, but it is practically impossible for even a partial unlocking to occur accidentally.

60 The described method of making the blanks by first providing the sections 17 with extension tabs 22 and then folding them over and gluing the tabs to the bottom or central section 12 and then cutting across 65 the tabs, possesses the important advantage

of rendering it impossible for said tabs to be secured in other than accurate positions to lock the edge of section 17 when a completed blank is set up for use. This is because the same crease lines which define 70 the temporary first folds prior to the adhesive connection of the tabs with the portion 12 also define the folds when the blanks are later folded to receptacle form.

When the blanks have been completed as 75 indicated in Figure 4 and the edges of sections 17 have been trimmed as described, they may, before storing or shipping them, be paraffined or waxed as explained in my application filed concurrently herewith, Se- 80 rial No. 551,030 if the boxes made from the blanks are to be used for containing substances such as referred to in that applica- 85 tion.

I do not limit myself to the relative proportions of the blank or box illustrated, nor to any specific use for the boxes. And it is to be understood that the terms "side" and "end" are employed solely for the sake 90 of brevity of description, and not for purposes of limitation.

Having now described my invention, I claim:

1. A box blank comprising a central portion having foldable side and end wall sections, the side wall sections having tongue flaps to be engaged inside the end wall sections when the latter are folded, said end wall sections having edge portions to bear on the central portion when folded, the tongue flaps being proportioned to permit the lower inside portions of the end wall sections to be flexed back under said tongue flaps, and locking stops carried by the central portion in position to necessitate the flexing back of the inside portions of the end wall sections when the edges of the latter are brought into engagement with said locking stops.

2. A box blank comprising a central portion having inner and outer side wall sections provided with tongue flaps at their ends, and end wall sections foldable over said flaps of the side wall sections, and locking stops adhesively secured to the central portion, the end flaps of the outer wall section being of less width than those of the inner wall sections, and the outer wall sections having end recesses adjacent their end flaps and in their side edges next to their ends.

3. A box member comprising a central portion having double-thick side walls provided with inwardly turned end flaps and double-thick end walls enclosing the end flaps of the side walls, edge portions of the end walls bearing on the central portion and locking stops secured to the central portion and overlapping the said edge portions of the end walls, the inwardly turned end flaps

being proportioned to cause the lower inner portions of the end walls to be flexed back when said edge portions are engaged by the locking stops.

5. That improvement in the method of making blanks for conversion into boxes having interlocked members, consisting in forming the blanks with extension tabs, folding the portions which carry the tabs onto inner portions of the blanks, securing the tabs to said inner portions and then cutting the material adjacent to the secured areas.

10 5. That improvement in the method of making blanks for conversion into boxes hav-

ing interlocked members, consisting in forming the blanks with extension tabs, folding the portions which carry the tabs onto inner portions of the blanks, adhesively securing predetermined areas of the tabs to said inner portions of the blanks, then cutting across the tabs at a predetermined distance from their secured areas, and then trimming the edges of the portions which originally carried the tabs.

15 20 25 In testimony whereof I have affixed my signature.

ELIE W. LABOMBARDE.
